UNITED STATES PATENT OFFICE.

HORACE F. STEVENS, OF ST. JACOB, ILLINOIS, ASSIGNOR OF ONE-HALF TO LILLIAN STEVENS AND ONE-FOURTH TO NELLIE STEVENS, BOTH OF ST. JACOB, ILLINOIS.

LAMP-BURNER.

1,140,415.

Specification of Letters Patent.

Patented May 25, 1915.

Application filed August 2, 1912, Serial No. 712,991. Renewed October 21, 1914. Serial No. 867,900.

To all whom it may concern:

Be it known that I, HORACE F. STEVENS, a citizen of the United States, residing at St. Jacob, in the county of Madison, State of Illinois, have invented certain new and useful Improvements in Lamp-Burners; and I do hereby declare the following to be a full, clear, and exact description of the invention, such as will enable others skilled in the art 10 to which it appertains to make and use the same.

The present invention is directed to improvements in lamp burners, and has for its object to provide a new and novel device for 15 holding the chimney upon the burner.

A further object of the invention is to so construct a device of this character that the chimney may be easily and quickly attached or removed from the burner.

20 With these and other objects in view, this invention resides in the novel features of construction, formations, combinations and arrangements of parts to be hereinafter more fully described, claimed and illustrated in 25 the accompanying drawing, in which:—

Figure 1 is a side elevation of the burner and a portion of the chimney showing the manner in which the same is secured to the burner, the chimney being partly in section.

30 Fig. 2 is a sectional view on line 2—2 of Fig. 1.

Referring to the drawing, the numeral 1 designates a burner, said burner being provided with an annular flange 2, said flange 35 being provided with a groove 3, the purpose of which will appear later.

The device for holding the chimney 4 in place upon the burner consists of a single length of resilient wire, the same being so 40 bent as to provide a plurality of pairs of vertical arms 5, the same being arranged in spaced parallel relation. The lower ends of the arms 5 are connected by horizontally disposed arms 6, which are slightly curved so

as to conform to the curvature of the flange 45 2. The upper ends of the arms 5 terminate in outwardly inclined portions 7, the upper ends of which are connected by outwardly curved bars 8 which engage the interior curved surface of the chimney 4. The horizontal arms 6 rest in the groove 3 in which they are secured, thus rigidly connecting the holder to the burner. The flange 2 is formed at diametrically opposite points with slots 9 which are adapted to be engaged by the 50 55 spring tongues 10 formed upon the lower edge of the flame deflecting cone 11 thus securely holding the same in place.

From this construction it will be seen that the chimney 4 is placed upon the burner so 60 that the curved bars 8 engage the inner surface thereof, and as the arms 5 are of a resilient nature, said bars will firmly bear against the chimney and hold the same upon the burner and against accidental displacement.

What is claimed is:—

In a chimney holder, the combination of a burner having an annular flange formed thereon, a groove formed in said flange, a 70 holder consisting of a single length of resilient wire and comprising a plurality of pairs of vertical arms arranged in parallel spaced relation, the lower ends of said arms being connected by horizontally disposed 75 arms, which are secured in the groove, said vertical arms having their upper ends terminating in outwardly inclined portions, said portions being connected at their upper ends by bars adapted to yieldably engage 80 the interior surface of a lamp chimney when the same is placed upon a burner.

In testimony whereof, I affix my signature, in presence of two witnesses.

HORACE F. STEVENS.
